UNITED STATES PATENT OFFICE.

JAMES TOTHAM, OF NEW HAVEN, CONNECTICUT, ASSIGNOR TO PECK BROS.
& CO., OF SAME PLACE.

DESIGN FOR A STANDARD FOR WASH-BASIN SLABS.

SPECIFICATION forming part of Design No. 21,724, dated July 19, 1892.

Application filed June 13, 1892. Serial No. 436,574. Term of patent 14 years.

To all whom it may concern:

Be it known that I, JAMES TOTHAM, of New Haven, in the county of New Haven and State of Connecticut, have invented a new Design 5 for a Support for Wash-Basin Slabs; and I do hereby declare the following, when taken in connection with the accompanying drawing and the letters of reference marked thereon, to be a full, clear, and exact description of the 10 same, and which said drawing constitutes part of this specification, and represents a face view.

This invention relates to a design for the standard arranged upon the floor beneath the 15 slab which carries the bowl for wash-basins, the design consisting in the configuration of the support, as hereinafter described, and shown in the accompanying illustration.

The standard consists of a central post *a*, 20 represented as resting upon a base *b* at the

bottom, having an ornamental collar *c* near its upper end, above which is a squared head *d*, represented as carrying an ornamental tip *e*. The head *d* is represented as carrying smaller heads *ff* at the right and left, and from these heads *ff* branches *g* extend, curved 25 upward and outward to the right and left, as shown in the accompanying illustration.

I claim—

The design for the standard for wash-basin 30 slabs, as herein described, and shown in the accompanying illustration.

In testimony whereof I have signed this specification in the presence of two subscribing witnesses.

JAMES TOTHAM.
